UNITED STATES PATENT OFFICE

151,523

DESIGN FOR A HANDBAG

Leon E. Meadow, New York, N. Y.

Application March 25, 1948, Serial No. 145,333

Term of patent 3½ years

(Cl. D37—3)

To all whom it may concern:

Be it known that I, Leon E. Meadow, a citizen of the United States of America, residing in New York city, county of New York, and State of New York, have invented a new, original, and ornamental Design for a Handbag, of which the following is a specification, reference being had to the accompanying drawing, forming part thereof, wherein,

I claim:

The ornamental design for a handbag, substantially as shown, and described.

LEON E. MEADOW.
